(57) **CLAIM**

The ornamental design for a leg press machine, as shown.

DESCRIPTION

FIG. 1 is rear perspective view of the leg press machine of the subject invention;

FIG. 2 is a front view thereof;

FIG. 3 is a rear view thereof;

FIG. 4 is a left side view thereof;

FIG. 5 is a right side view thereof; and,

FIG. 6 is a top view thereof.

1 Claim, 6 Drawing Sheets

*FIG. 1****FIG. 2***FIG. 3

FIG. 4***FIG. 5****FIG. 6*
